(57) **CLAIM**

The ornamental design for a fastener positioning device, as shown and described.

DESCRIPTION

FIG. 1 is top, front, left side perspective view of the fastener positioning device embodying the new design;

FIG. 2 is a right side view thereof, the left side view being a mirror image thereof;

FIG. 3 is a front view thereof;

FIG. 4 is a rear view thereof;

FIG. 5 is a top view thereof; and,

FIG. 6 is a bottom view thereof.

The dot-dash-dot broken lines rendered in the drawings, showing of the screw, illustrates the environment of the claimed design and forms no part thereof.
